[57] CLAIM

The ornamental design for an inline handle support, as shown and described.

DESCRIPTION

FIG. 1 is a perspective view of inline handle support, showing our new design;

FIG. 2 is a top plan end view thereof, the bottom plan end view being identical;

FIG. 3 is a right side elevational view thereof;

FIG. 4 is a left side elevational view thereof; and,

FIG. 5 is a front side elevational view thereof, the rear side being a mirror image.
